UNITED STATES PATENT OFFICE.

JOHN GYLYWAICHUK, OF TOLSTOI, MANITOBA, CANADA.

DESIGN FOR A TIE-PIN.

51,233.

Specification for Design.

Patented Sept. 4, 1917.

Application filed May 31, 1917. Serial No. 172,106. Term of patent 3½ years.

To all whom it may concern:

Be it known that I, JOHN GYLYWAICHUK, a subject of the King of England, residing at Tolstoi, in the Province of Manitoba and Dominion of Canada, have invented a new, original, and ornamental Design for Tie-Pins, of which the following is a specification, reference being had to the accompanying drawing, forming part thereof.

The figure is a front elevational view of a tie pin showing my new design.

I claim:—

The ornamental design for a "tie pin" as shown.

JOHN GYLYWAICHUK.
